SPRAY TYPE LAWN SPRINKLER

George W. Rienks, Denver, Colo.

Application July 24, 1953, Serial No. 26,119

Term of patent 7 years

(Cl. D91—1)

To all whom it may concern:

Be it known that I, George W. Rienks, a citizen of the United States of America, residing at Denver, in the county of Denver and State of Colorado, have invented a new, original, and ornamental Design for a Spray Type Lawn Sprinkler, of which the following is a specification, reference being had to the accompanying drawing, forming a part thereof.

In said drawing:

Fig. 1 is a top plan view of a spray type lawn sprinkler showing my new design; and

Fig. 2 is a side elevational view thereof.

I claim:

The ornamental design for a spray type lawn sprinkler, substantially as shown.

GEORGE W. RIENKS.
